THERMOSTAT

Hugh Kelly, Milwaukee, Wis., assignor to Perfex Corporation, Milwaukee, Wis., a corporation of Wisconsin

Application December 27, 1948, Serial No. 150,367

Term of patent 14 years

(Cl. D52—7)

To all whom it may concern:

Be it known that I, Hugh Kelly, a citizen of the United States, and a resident of Milwaukee, in the county of Milwaukee and State of Wisconsin, have invented a new, original, and ornamental Design for a Thermostat, of which the following is a specification, reference being had to the accompanying drawing, forming a part thereof:

Fig. 1 is a perspective view of a thermostat showing my new design;

Fig. 2 is a front elevational view thereof;

Fig. 3 is a side elevational view thereof; and
Fig. 4 is a top view.

I claim:

The ornamental design for a thermostat, substantially as shown.

HUGH KELLY.
